UNITED STATES PATENT OFFICE

GILBERT E. ROGERS, OF ROCKAWAY, NEW JERSEY

FUSE FOR PROJECTILES

Application filed May 22, 1929. Serial No. 365,204.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

5 The subject of this invention is a fuse for projectiles, particularly designed as an improvement on that type of fuse whose distinguishing characteristic is a completely assembled plunger unit carrying a bore safe

10 firing pin.

The principal object of this invention is to provide a plunger of the type specified which is especially applicable to a combination point detonating and percussion fuse.

15 With the foregoing and other objects in view, the invention resides in the novel arrangement and combination of parts and in the details of construction hereinafter described and claimed, it being understood that 20 changes in the precise embodiment of the invention herein disclosed may be made within the scope of what is claimed without departing from the spirit of the invention.

A practical embodiment of the invention is 25 illustrated in the accompanying drawing, wherein:

Fig. 1 is a longitudinal sectional view of a fuse constructed in accordance with the invention showing the parts adjusted for instantaneouse action;

Fig. 2 is a fragmentary, longitudinal sectional view showing the parts in position for delay action firing;

Fig. 3 is a sectional view of the plunger unit taken at right angles to Fig. 1.

Referring to the drawing by characters of reference:

There is shown a fuse casing 5 in which is 40 mounted an axial impact striker 6 capable of being inoperated by any means not illustrated since the same is old and well-known in the art, but otherwise operable on impact to function a detonator 7 which is so mounted in a movable carrier 8 that it may be positioned to communicate with a booster charge 9 in the rear of the casing. A spring 10, confined between the fixed part of the casing and a collar 11 on the striker, restores the striker 45 to the armed position when the force of set-

back has ceased and maintains it in this position against air pressure during flight.

Mounted in a cavity 12 in the fuse casing, directly in front of the adaptor 13 carrying the detonator and booster, is a plunger unit 55 consisting of a telescopically arranged percussion plunger 14 and guide 15. The guide is in the form of a bushing partially inserted in a central aperture 16 in the plunger and provided with an annular flange 17 whose margin is engaged when the guide is extended by a spring 18 by the inturned rim 19 of a sheath 20 encasing the plunger.

The two members of the plunger unit are 60 positively locked in the extended position by means of centrifugally releasable bolts 21 arranged oppositely in the plunger and normally projected by their springs 22 into the central aperture 16 where they are in position to oppose inward movement of the guide 70 15. The bolts when in the normal position contact the reduced portion 23 of the striker which must pass through the guide and plunger in order to reach the detonator.

The percussion plunger 14 carries a non- 75 axial delay explosive train 24 which is in communication through an inclined flash passage 25 with the detonator 8. A firing pin 26, fixed in the fuse casing forwardly of the plunger unit, projects through an aperture 27 80 in the flange 17 of the guide and has its point disposed in a guide passage 28 in the plunger to insure alignment with the explosive train by preventing rotary movement 85 of the plunger unit during the forward displacement of the plunger resulting from retardation of the projectile. Relative rotary movement of the plunger and guide is further prevented by a lug 29 on the flange 90 of the guide member fitted into a groove 30 in the plunger.

When the striker is adjusted for operation, as in Fig. 1, it will move rearwardly on setback, exerting a pressure on the guide member which, in turn, is transmitted to the bolts 95 21 to increase their resistance to the action of centrifugal force until the force of setback has abated.

When inserting the assembled plunger unit 100 into the cavity, it receives the fixed firing pin

26 and the portion 23 of the striker which is of sufficient length to be introduced between the bolts 21 even when the striker is in its inoperative position, as shown in Fig. 2.

5 The plunger unit, after being placed in the cavity, is firmly held against the floor thereof by a disc 31 which is assembled with the adaptor 13.

I claim:

- 10 1. In a combination fuse, a fuse casing formed with a cavity, an adaptor closing the cavity, a detonator in the adaptor, a plunger unit in the cavity including a percussion plunger and a guide member cooperating to limit their extension, a spring between the percussion plunger and guide member, centrifugally releasable bolts carried by the plunger for holding the percussion plunger and guide in extended position, a delay explosive train eccentrically carried by the percussion plunger, an axially mounted striker in the fuse casing passing centrally through the plunger unit and a firing pin fixed in the fuse casing in line with the delay explosive train.
- 15 2. In a combination fuse, a fuse casing formed with a cavity, a plunger unit in the cavity including a percussion plunger and a guide member cooperating to limit their extension, a spring between the percussion plunger and guide member, centrifugally releasable bolts carried by the plunger for holding the percussion plunger and guide in extended position, a delay explosive train eccentrically carried by the percussion plunger, an axially mounted striker in the fuse casing passing centrally through the plunger unit and a firing pin fixed in the fuse casing in line with the delay explosive train.
- 20 3. In a combination fuse, a fuse casing formed with a cavity, a plunger unit in the cavity including a percussion plunger and a guide member cooperating to limit their extension, a spring between the percussion plunger and guide member, centrifugally releasable bolts carried by the plunger for holding the percussion plunger and guide in extended position, a delay explosive train eccentrically carried by the percussion plunger, an axially mounted striker in the fuse casing passing centrally through the plunger unit and a firing pin fixed in the fuse casing in line with the delay explosive train.
- 25 4. In a combination fuse, a fuse casing formed with a cavity, a plunger unit in the cavity including a percussion plunger and a guide member cooperating to limit their extension, a spring between the percussion plunger and guide member, centrifugally releasable bolts carried by the plunger for holding the percussion plunger and guide in extended position, a delay explosive train eccentrically carried by the plunger, an axially mounted striker in the fuse casing passing centrally through the plunger unit and a firing pin fixed in the fuse casing in line with the delay explosive train.
- 30 5. In a combination fuse, a fuse casing formed with a cavity, a plunger unit in the cavity including a percussion plunger and a guide member cooperating to limit their extension, a spring between the percussion plunger and guide member, centrifugally releasable bolts carried by the plunger for holding the percussion plunger and guide in extended position, a delay explosive train eccentrically carried by the plunger, an axially mounted striker in the fuse casing passing centrally through the plunger unit and a firing pin fixed in the fuse casing in line with the delay explosive train.
- 35 6. In a combination fuse, a fuse casing formed with a cavity, a plunger unit in the cavity including a percussion plunger and a guide member cooperating to limit their extension, a spring between the percussion plunger and guide member, centrifugally releasable bolts carried by the plunger for holding the percussion plunger and guide in extended position, a delay explosive train eccentrically carried by the plunger, an axially mounted striker in the fuse casing passing centrally through the plunger unit and a firing pin fixed in the fuse casing in line with the delay explosive train.
- 40 7. In a combination fuse, a fuse casing formed with a cavity, a plunger unit in the cavity including a percussion plunger and a guide member cooperating to limit their extension, a spring between the percussion plunger and guide member, centrifugally releasable bolts carried by the plunger for holding the percussion plunger and guide in extended position, a delay explosive train eccentrically carried by the plunger, an axially mounted striker in the fuse casing passing centrally through the plunger unit and a firing pin fixed in the fuse casing in line with the delay explosive train.
- 45 8. In a combination fuse, a casing, a plunger in the casing, means carried by and releasably locked to the plunger and engaging the casing for restraining the plunger against movement, an independently movable striker passing through the plunger and an element of a firing mechanism carried by the plunger.
- 50 9. In a fuse, a casing, a plunger in the casing, a restraining member engaging the casing and normally locked to the plunger, an independently movable striker passing through the restraining member and plunger and arrested during setback by the restraining member.
- 55 10. In a fuse, a casing, a plunger in the casing, a restraining member engaging the casing and normally locked to the plunger and an independently movable striker passing through the restraining member and plunger.
- 60 11. In a fuse, a plunger unit including a percussion plunger and a guide member cooperating to limit their relative extension and having a central passage to accommodate auxiliary mechanism, means for releasably locking said members in extended position, and an element of a firing mechanism, eccentrically carried by the plunger.

through the guide in line with the delay explosive train.

5. In a combination fuse, a fuse casing formed with a cavity, a plunger unit including a percussion plunger and a guide member cooperating to limit their extension, means for releasably locking the plunger and guide in extended position, a delay explosive train eccentrically carried by the plunger, an axially movable striker in the fuse casing passing through the plunger unit and a firing pin fixed in the fuse casing and extending through the guide in line with the delay explosive train. 75

6. In a combination fuse, a fuse casing formed with a cavity, a plunger unit including a percussion plunger and a guide member cooperating to limit their extension, means for releasably locking the plunger and guide in extended position, a delay explosive train eccentrically carried by the plunger, a striker in the fuse casing passing through the plunger unit and a firing pin fixed in the fuse casing and extending through the guide in line with the delay explosive train. 85

7. In a combination fuse, a fuse casing formed with a cavity, a plunger unit including a percussion plunger and a guide member cooperating to limit their extension, means for releasably locking the plunger and guide in extended position, a delay explosive train eccentrically carried by the plunger, a striker in the fuse casing passing through the plunger unit and a firing pin fixed in the fuse casing in line with the delay explosive train. 95

8. In a combination fuse, a casing, a plunger in the casing, means carried by and releasably locked to the plunger and engaging the casing for restraining the plunger against movement, an independently movable striker passing through the plunger and an element of a firing mechanism carried by the plunger. 100

9. In a fuse, a casing, a plunger in the casing, a restraining member engaging the casing and normally locked to the plunger, an independently movable striker passing through the restraining member and plunger and arrested during setback by the restraining member. 110

10. In a fuse, a casing, a plunger in the casing, a restraining member engaging the casing and normally locked to the plunger and an independently movable striker passing through the restraining member and plunger. 115

11. In a fuse, a plunger unit including a percussion plunger and a guide member cooperating to limit their relative extension and having a central passage to accommodate auxiliary mechanism, means for releasably locking said members in extended position, and an element of a firing mechanism, eccentrically carried by the plunger. 125
